UNITED STATES PATENT OFFICE.

HENRY E. SMITH, OF NEWARK, NEW JERSEY.

DESIGN FOR A BUCKLE.

SPECIFICATION forming part of Design No. 27,134, dated June 1, 1897.

Application filed April 17, 1897. Serial No. 632,672. Term of patent 7 years.

To all whom it may concern:

Be it known that I, HENRY E. SMITH, a citizen of the United States, residing at Newark, in the county of Essex and State of New Jersey, have invented and produced a new and original Design for a Pearl Buckle, of which the following is a specification, reference being had to the accompanying drawings, showing a part thereof.

Figure 1 is a plan view of a buckle showing my design. Fig. 2 is a cross-section thereof, and Fig. 3 is a front edge view.

A leading feature of my design consists in a panel having the appearance of being inserted in and extended lengthwise and across the front bar of the buckle-loop, the said panel contrasting with the side portions of the loop.

Another leading feature consists in a panel having the appearance of being inserted in and extended lengthwise of the front bar of the buckle-loop, the junction between the ends of the panel and the sides of the loop being on diagonal lines, the said panel contrasting with the side portions of the loop.

1 designates the side portions of the buckle-loop, consisting of metal and connected together at the rear ends by a cross-bar 2, from which a tongue 3 extends, the rear ends of said side portions being curved downward, so 30 that the cross-bar is below the plane of the side portions. The front bar of the loop has a panel 4 extended lengthwise and across the front bar. The junctions between the side portions and panel are in diagonal lines, and 35 raised ornaments appear at the ends of the panel. The panel consists of mother-of-pearl, and therefore contrasts with the side portions of the loop. Viewed from the front the panel appears as having its ends inserted under overlapping tongues of the side portions.

I claim—

The design for a pearl buckle, substantially as shown and described.

HENRY E. SMITH.
